UNITED STATES PATENT OFFICE.

JACOB S. VOLLMER, OF NEWARK, OHIO.

AUTOMATIC CUT-OFF VALVE FOR GAS-STOVES.

1,032,972.

Specification of Letters Patent. Patented July 16, 1912.

Application filed October 26, 1911. Serial No. 656,945.

To all whom it may concern:

Be it known that I, JACOB S. VOLLMER, a citizen of the United States, residing at Newark, in the county of Licking and State of Ohio, have invented certain new and useful Improvements in Automatic Cut-Off Valves for Gas-Stoves; and I do declare the following to be a full, clear, and exact description of the invention, such as will enable others skilled in the art to which it app pertains to make and use the same.

This invention relates to improvements in automatic cut off valves for gas stoves.

One object of the invention is to provide an automatic cut off of this character having an improved construction and arrangement of valve adapted to be opened by the weight of a cooking utensil or other object placed on the burner of the stove and to be automatically closed when the object is removed from the burner, means being provided whereby sufficient gas is permitted to flow through the burner to maintain a very small light whereby when the valve is opened full in the manner described, the larger volume of gas will be ignited.

Another object is to provide an improved construction and arrangement of valve opening lever having an adjustable valve engaging mechanism whereby the valve may be opened to a greater or less extent, thus regulating the size of the blaze.

With these and other objects in view the invention consists of certain novel features of construction, and the combination and arrangement of parts as will be more fully described and claimed.

In the accompanying drawings: Figure 1 is a vertical sectional view through a portion of a gas stove showing the application of the invention; Fig. 2 is a top plan view of the same; Fig. 3 is an enlarged vertical longitudinal sectional view through the valve of the attachment showing the valve in closed position; Fig. 4 is a similar view showing the valve in open position; Fig. 5 is a cross sectional view on the line 5—5 of Fig. 3; Fig. 6 is a detail perspective view of the valve removed from the casing; Fig. 7 is a similar view of the valve opening lever.

In the embodiment of the invention I provide a valve casing 1 which is preferably

in the form of a tube or cylinder having its bore at the upper end enlarged to form a recess 2 the purpose of which will be hereinafter described. The upper recessed end of the valve casing is exteriorly threaded and adapted to be screwed onto said end is a cap 3. In one side of the valve casing is formed a threaded passage 4 which communicates with the recess 2 or enlarged bore of the casing near its inner end as shown. With said threaded passage is adapted to be engaged a branch gas supply pipe 5 the outer end of which is connected with the main gas supply pipe 6. In the pipe 5 is arranged a cut off valve 7 whereby the flow of gas from the main supply pipe to the valve casing may be cut off. In the opposite side of the casing 1 near its lower end and communicating with the bore of said tube is a gas conducting tube 8 the outer end of which is engaged with the mixing chamber 9 and gas conducting tube 10 of the burner 11 which is arranged in suitable position beneath the body or frame 12 of the gas stove as shown. The burner 11 may be of any suitable construction and is here shown in the form of a tubular ring perforated in its upper side to form gas discharge openings.

Slidably mounted in the casing 1 is a tubular or hollow cylindrical valve 13 the upper end of which is closed by a circular guide plate 14 secured to said end of the valve in any suitable manner. The plate 14 has formed therein a small gas passage 15 the purpose of which will be hereinafter described. In one side of the valve near its upper end is formed a gas inlet port 16, while near the lower end of the valve and in the opposite side thereof from the port 16 is formed an elongated gas discharge port 17. The valve when arranged in the casing has its lower end forming its stem projecting a suitable distance beyond the lower end of the casing and when it is desired to open the valve it is necessary to force the valve upwardly in the casing until the guide plate 14 is above the discharge end of the pipe 5 as shown in Fig. 4 of the drawings, in which position the inlet port 16 of the valve will be brought into register with the inlet pipe 5 and the discharge port 17

of the valve will be brought into full register with the gas conducting tube 8 whereupon the gas may flow to the mixer 9 and the burner.

- 5 In order to automatically open the valve, I preferably employ a bell crank lever 19 which is pivotally mounted intermediate of its ends by a pivot screw 19' or other suitable means to one side of the gas conducting tube 10 of the burner or to some other suitable support. The lever 19 has its inner end bent upwardly at a right angle and projected through the annular burner 11. The right angular projecting end of the lever 19
- 10 extends a suitable distance above the top of the stove and has arranged thereon a plate 20 with which the cooking utensil or other object is engaged when placed over the burner. The outer end of the lever is bent
- 15 to bring said end beneath the stem of the valve 13 and in said end of the lever is formed a threaded opening 21 through which is adapted to be screwed a valve operating screw 22 the upper end of which is
- 20 adapted to engage the stem of the valve, said stem of the valve being preferably enlarged to form an increased bearing surface for the screw. By thus constructing and arranging the lever 19 it will be seen that
- 25 when a cooking utensil or other weight is placed on the stove over the burner and into engagement with the plate 20, that the lever will be rocked thus causing the screw 22 in the outer end thereof to lift or force the
- 30 valve upwardly in the casing until the ports 16 and 17 are brought opposite to the inlet and discharge ports of the casing as hereinbefore described. By adjusting the screw 22 in the end of the lever the stroke of the
- 35 valve may be regulated to bring the discharge port 17 into more or less complete register with the inner end of the gas conducting tube 8, thus controlling the flow of the gas through said pipe and to the burner.
- 40 45 When the weight of the cooking utensil or other object is removed from the stove the valve is immediately brought to a closed position by means of a coiled spring 23 arranged in the enlarged upper bore or recess
